Term of patent 14 years

(Cl. D33—14)

FIG. 1.

FIG. 3.

FIG. 2.

FIG. 4.

Figure 4 is a top plan view with three-fourths of the table top broken away in order better to illustrate the bottom detail extending parallel to the table top.

We claim:

The ornamental design for an umbrella table, as shown.
